UNITED STATES PATENT OFFICE.

FREDERICK AUGUST GROENKE, OF MELROSE PARK, ILLINOIS.

LIFE-PRESERVER.

SPECIFICATION forming part of Letters Patent No. 668,177, dated February 19, 1901.

Application filed April 4, 1900. Serial No. 11,437. (No model.)

To all whom it may concern:

Be it known that I, FREDERICK AUGUST GROENKE, a citizen of the United States, and a resident of Melrose Park, county of Cook, 5 and State of Illinois, have invented certain new and useful Improvements in Life-Preservers, of which the following is a specification, reference being had to the accompanying drawings, forming a part thereof, in which o similar letters of reference indicate corresponding parts.

This invention relates to an improved life-preserver of the class adapted to float persons unskilled in the art of swimming to prevent 5 them drowning; and the object of the invention is to provide a device of this character which is adapted to be deflated and folded for storage within a small space and which can readily be inflated by a wearer after it is o attached to the body, whereby a traveler can always keep an efficient life-preserver readily at hand.

The invention will be hereinafter fully described, and specifically set forth in the annexed claim.

In the accompanying drawings, forming part of this specification, Figure 1 is a plan view of my improved life-preserver, showing the same in inflated condition; and Fig. 2 is o a cross-sectional elevation taken on line $x-x$ of Fig. 1.

In the practice of my invention I employ an air chamber or compartment A and a communicating approximately U-shaped tubular air-channel A', which leads into the said chamber A, at each end thereof, to form in conjunction with the compartment A a continuous air-compartment adapted to encircle the body of a person.

o Communicating with the air-channel A' is an ordinary air-inlet valve B, which is normally closed by means of a screw-cap B', which cap is attached to the life-preserver by means of a chain b, which engages a loop a, formed 5 integral with the tubular channel A', whereby the cap cannot be lost during the operation of inflating the device.

As a means for inflating the device I employ an ordinary air-pump C, which is se-

cured within a grooved block a', formed integral with the air-channel A', and the pump is securely fastened within the groove of the said block by means of straps a², which are preferably vulcanized to the block a' to keep the pump permanently in place. 50

The pump C is supplied with a flexible tube c and a screw-nozzle c' for engagement within the casing of the valve B to supply air to the device.

The material employed in the construction 60 of the air-chamber A and its integrally-formed communicating channel A' is preferably rubber; but it is obvious that a combination of rubber and canvas or any suitable flexible material which is impervious to the action of 65 water may be employed.

In use the device is placed around the body of a person beneath his arms while it is in a deflated and limp condition. The nozzle c' is then screwed to the air-valve casing, whereupon the wearer can pump any required quantity of air into the device to form an efficient life-preserver. 70

I do not confine myself to the specific details of contour or mechanical construction 75 of the parts forming the device, as it is obvious that under the scope of my invention I am entitled to slight structural variations.

Having thus described my invention, what I claim as new, and desire to secure by Letters 80 Patent, is—

As a life-preserver the combination of an air-compartment, an approximately U-shaped air-channel having its two ends leading thereto, and an air-inlet valve leading to said U-shaped channel, and an air-pump securely attached thereto, whereby the device can be inflated or expanded by a wearer after it is attached to his body, substantially as shown and described. 85

In testimony that I claim the foregoing as my invention I have signed my name, in presence of two witnesses, this 15th day of March, 1900.

FREDERICK AUGUST GROENKE.
